UNITED STATES PATENT OFFICE.

HOWELL D. PRATT, OF PHILADELPHIA, PENNSYLVANIA, ASSIGNOR TO LINK-BELT COMPANY, OF CHICAGO, ILLINOIS, A CORPORATION OF ILLINOIS.

STORAGE SYSTEM.

Application filed January 31, 1921. Serial No. 441,242.

To all whom it may concern:

Be it known that I, HOWELL D. PRATT, a citizen of the United States, residing in Philadelphia, Pennsylvania, have invented 5 certain Improvements in Storage Systems, of which the following is a specification.

The object of my invention is to design a storage system having a bin and a storage floor and to provide means whereby granular 10 material can be discharged into the bin or onto the piling floor and can be removed from the piling floor and discharged into the bin.

This object I attain in the following 15 manner, reference being had to the accompanying drawings, in which:

Fig. 1 is a diagrammatic view, showing the bin in section and the parts arranged to remove material from the piling floor and 20 discharge it into the bin;

Fig. 2 is a view similar to Fig. 1, showing the means for discharging the material onto the piling floor direct from the conveyer;

Fig. 3 is an enlarged sectional view of the 25 movable elevator, showing the chute down which the material flows, or up which the material is carried by the scoop;

Fig. 4 is a view of a modification of the 30 invention showing an elevator at one side of the inclined chute; and Fig. 5 is a sectional view of the belt conveyer and chute.

1 is a storage bin, in the present instance, mounted on posts 2 adjacent a track 23. 35 24 is a chute through which material is discharged from a belt conveyer 21 through side passages 24^a and 24^b. The tripping mechanism for the belt shown in Fig. 5 is an ordinary form of tripping device, and a valve 25 is provided for closing either 40 side passage. This storage bin is arranged at such a height and in such a position that coal, or like material, can be discharged from the bin by gravity, or by means of a conveyer, to a boiler, or other furnace, where 45 it is consumed. In many instances a surplus quantity of material is delivered and the bin has not the capacity to hold it, therefore, a piling floor, such as 3, is provided, preferably adjacent to the bin, for receiving 50 the surplus coal, or other material. On one longitudinal edge of the bin 1 is a track 4 and at the edge of the piling floor is a track 5. 6 is an inclined structure supported by 55 wheels 7 adapted to the rail 4 and wheels 8 adapted to the rail 5. This structure can

be moved longitudinally in respect to the bin and piling floor. On the structure is a chute 9 extending from the chute 24 to the piling floor 3, and a scoop 10 is arranged to travel over this inclined chute 9 and over 60 the surface of the pile of material on the piling floor. This scoop may be arranged to remove material from the pile and discharge it into the bin, as in Fig. 1, or it may receive material which flows down the 65 chute 9 and over the pile and discharge it thereon.

On the structure 6 is a platform 11 supporting the rope drums 12 and 12^a and the operating motor 13, and on this platform 70 are the levers for controlling the drums, which are manually operated by a person standing on the platform. A rope 14 passes from the drum 12 around a sheave 15 pivotally connected to a short post 16 at the far 75 end of the piling floor, as shown in Fig. 1, or to a mast 17, as shown in Fig. 2. This rope 14 returns and is attached to one end of the scoop 10. A rope 18 extends from the drum 12^a over a sheave 19 at the upper 80 end of the structure 6 and returns under a guide wheel 20 to the opposite end of the scoop 10.

In Fig. 1, the rope 14 is shown as attached to the rear end of the scoop and the 85 rope 18 is shown as attached to the forward end. In this position, when the rope mechanism is operated the scoop receives material from the pile on the piling floor 3 and carries it up the inclined chute 9, discharging it at the upper end of the bin 1.

In Fig. 2, the rope 18 is shown as attached to the rear of the scoop and the rope 14 is shown as attached to the forward end thereof. The material, as it is discharged 95 from the chute 4, flows down the inclined chute 9 and the scoop removes the material from the bottom of the chute and carries it over the material of the pile and discharges it at the apex of the pile, allowing 100 it to flow by gravity free from the chute.

When the bin is comparatively short and the piling floor is designed to receive only a conical pile, then the structure 6 may be fixed as regards any longitudinal movement, 105 but bins are generally of considerable length and the piling floor, adjacent a bin, is also of considerable length so that, by mounting the chute structure on wheels, the mechanism can be moved longitudinally in order 110

to utilize the entire capacity of the bin, as well as the piling floor.

In some instances, I may locate a bucket elevator 25 at one side of the chute 9 of the structure 6, as shown in Fig. 4, so that the scoop need only carry material to the base of the elevator, the elevator receiving the material and carrying it to the bin. The chute, in this case, is used only as a discharge chute from the belt conveyer to the piling floor.

I claim:

1. The combination of a bin; a piling floor, and inclined structure extending from the top of the bin to the piling floor; means for distributing material on the piling floor; a conveyer above the bin; and means for discharging material carried by the conveyer into the bin or onto the inclined structure.

2. The combination of a bin; a piling floor, and inclined structure extending from

the top of the bin to the piling floor; a chute on said inclined structure; an overhead conveyer; means for discharging material from said conveyer into the bin or onto the inclined chute; a scoop arranged to travel over the inclined chute and onto the piling floor; and means for operating the scoop.

3. The combination of a bin; a piling floor, and inclined structure at the side of the bin and having a chute extending from the top of the bin to the piling floor; longitudinal rails on which the structure is mounted so that it can be moved longitudinally in respect to the bin and piling floor; an overhead conveyer; means for discharging material carried by the conveyer into the bin or onto the chute; a scoop; and means for operating the scoop, said scoop being arranged to travel over the inclined chute and onto the piling floor.

HOWELL D. PRATT.
